(57) CLAIM

The ornamental design for a magnetic clasp for a bra, as shown and described.

DESCRIPTION

FIG. 1 is a front view of a magnetic clasp for a bra, shown twice and attached to a bra;

FIG. 2 is a front perspective view of the magnetic clasp for a bra, shown separated from the bra;

FIG. 3 is a front view thereof;

FIG. 4 is a side view thereof; and,

FIG. 5 is an opposite side view thereof.

The broken line outline of the bra in FIG. 1 depicts the environment associated with the magnetic clasp for a bra and forms no part of the claimed design.

1 Claim, 2 Drawing Sheets
